UNITED STATES PATENT OFFICE.

ALBERT L. SWETT, OF MEDINA, NEW YORK.

DOOR-HANGER.

SPECIFICATION forming part of Letters Patent No. 436,197, dated September 9, 1890.

Application filed April 25, 1890. Serial No. 349,424. (No model.)

To all whom it may concern:

Be it known that I, ALBERT L. SWETT, a citizen of the United States, residing at Medina, in the county of Orleans and State of New York, have invented new and useful Improvements in Door-Hangers, of which the following is a specification.

This invention relates to that class of door-hangers which are provided with a horseshoe-shaped frame, having its ends arranged upwardly and doubled back to form supports for two rider-bars which rest on the roller-journals.

The objects of my invention are to provide strong and durable rider-bars which will securely confine the roller, and which can be constructed at comparatively small expense, and to provide simple means for removing the roller from the rider-bars when desired.

In the accompanying drawings, Figure 1 is a side elevation of my improved door-hanger. Fig. 2 is an end elevation of the hanger, showing the door and rail in section. Fig. 3 is a vertical section in line $x x$, Fig. 1. Fig 4 is a top plan view of the hanger. Fig. 5 is a longitudinal section of the same. Fig. 6 is a horizontal section in line $y y$, Fig. 1, looking upward. Fig. 7 is a cross-section of one of the rider-bars, on an enlarged scale.

Like letters of reference refer to like parts in the several figures.

A represents the door, and B the overhead beam provided with a rail b , on which the hanger runs.

C represents the horseshoe-shaped frame of the door-hanger secured with its curved lower portion to the door, and having its ends c extending upwardly on one side of the beam and rail and curved over the latter and projecting downwardly at the rear side of the hanger, as represented at c' .

D D' represent two horizontal rider-bars secured, respectively, to the upwardly-extending front portions c and the downwardly-projecting rear ends c' of the frame. These rider-bars are straight channel-bars, preferably formed of rolled steel, and arranged with their channeled or grooved sides inwardly or toward each other. The upper flange d of each rider-bar is made horizontal on its lower side, so as to stand at right angles to the inner side of the channel-bar, and beveled on

its upper side, while the lower flange d' is preferably beveled on both sides, as clearly represented in Fig. 7.

55

E represents the roller, preferably mounted loosely on the shaft e , which latter projects on both sides of the roller and supports both rider-bars. The latter rest with the lower horizontal faces of their top flanges d upon the ends or journals of the shaft e . The upper sides of these flanges are beveled for the purpose of permitting the bars to be rolled, and the lower flanges d' are beveled for the same purpose.

65

The top and bottom flanges are cut away at both ends of each rider-bar to permit the frame to rest against the webs of the bars, as represented in Fig. 5.

The lower flanges d' of the rider-bars are provided, preferably at both ends, with longitudinal slits f , extending inwardly from the ends of each flange, as represented in Fig. 6, a sufficient distance to permit the lips g so formed to be bent down, as represented in 75 dotted lines in Fig. 5.

When it is desired to remove the roller from the hanger for renewing the roller or shaft or for any other purpose, the two lips at one end of the hanger are bent down sufficiently 80 to permit the roller to be removed, and when the roller has been replaced they are bent back to a horizontal position to confine the roller between the rider-bars.

These rider-bars are very strong, light, and durable, and can be easily secured to the hanger-frame, constituting therewith a light and rigid frame.

I claim as my invention—

1. The combination, with the roller and the 90 hanger-frame, of rider-bars provided with a releasing-lip which can be bent out of its normal position to permit the roller to be withdrawn, substantially as set forth.

2. The combination, with the roller and the 95 hanger-frame, of channeled rider-bars having their lower flanges provided with end slits forming releasing-lips, substantially as set forth.

Witness my hand this 4th day of April, 1890. 100
ALBERT L. SWETT.
